SLIDING WINDOW CONSTRUCTION

Theodore Hauck, Bellmore, N. Y., assignor to General Bronze Corporation, Garden City, N. Y.

Application April 1, 1950, Serial No. 153,350

14 Claims. (Cl. 20—52.2)

1

This invention relates to sliding window constructions. The invention has particular application to a practicable and relatively inexpensive arrangement of slideable window sashes so constructed that the sashes may be wholly removed from the frames to leave an unobstructed window opening without disturbing the window frame. In the exemplary form described herein the invention is embodied in a window construction having a pair of horizontally slideable sashes, one being an inner sash and the other being an outer sash, each of a size to close approximately one half of the window opening and with a lock mechanism at their meeting rails whereby the sashes may be locked so as to seal completely the window opening. When unlocked either sash may be moved along individual sash guiding channels in the window frame to adjusted, partially open positions and, as will be brought out more fully hereinafter, either sash or both may be wholly removed from the frame by a simple lifting operation to leave an unobstructed window opening. It will of course be apparent to those skilled in the art that the invention or certain aspects of it may readily be adapted to and embodied in other window constructions and units differing in various particulars from the one set forth in detail hereinafter.

It is an object of the present invention to provide a commercially-feasible low-cost window construction which will require no special maintenance or attention and in which the sashes are easily movable to adjusted positions or may even be completely removed to leave a wholly unobstructed window opening. A further objective is to provide a simple sliding window sash arrangement which will form a complete bar to the entrance of weather when in its closed position and which may be securely locked in any one of several adjusted relationships. A further objective resides in the provision of a novel weather sealing relationship which promotes easy window operation over a long period of use and at the same time assures full protection against entrance of moisture and leakage of cold air. Other objects will in part be pointed out as the description proceeds and will in part become apparent therefrom.

The invention accordingly consists in the features of construction, combinations of elements, methods of operation and arrangements of parts as will be exemplified in the structures and sequences and groups of related steps to be herein-after described and the scope of the applica-

tion of which will be set forth in the accompanying claims.

In this specification and the accompanying drawings I have shown and described a preferred embodiment of my invention and suggested various modifications thereof; but it is to be understood that these are not intended to be exhaustive nor limiting of the invention, but, on the contrary, are given for purposes of illustration in order that others skilled in the art may fully understand the invention and the principles thereof and the manner of applying it in various forms, each as may be best suited to the conditions of a particular use.

15 In the drawings:

Figure 1 is an elevation showing a window construction embodying my invention;

Figure 2 is an enlarged fragmentary cross section taken along the lines 2—2 of Figure 1;

Figure 3 is an enlarged fragmentary cross section taken along the lines 3—3 of Figure 1;

Figure 4 is a sectional view taken along the lines 4—4 of Figure 3;

Figure 5 is a fragmentary sectional view on an enlarged scale taken along the lines 5—5 of Figure 1;

Figure 6 is a fragmentary view taken along the lines 6—6 of Figure 5;

Figure 7 is a view of a locking construction illustrated in Figure 5 taken at right angles to the view of Figure 5; and

Figure 8 is a view of a catch mechanism taken along the line 8—8 of Figure 2.

Figure 1 illustrates a window frame generally indicated at 20 consisting of a header 22, a sill 24 and jambs 26 and 28. In window frame 20 are slidably mounted an inner sash 30 and an outer sash 32. Sash 30 is an inner sash with respect to sash 32 in the sense that, as viewed in Figure 1, when sash 30 is moved to the right as will be developed more fully below, sash 30 lies inside of sash 32 (see Figures 2 and 5). Sash 30 includes an upper rail 34, a lower rail 36, a vertical rail 38 and a meeting rail 40. Sash 32 similarly includes an upper rail 42, a lower rail 44, a vertical rail 46 and a meeting rail 48. In the form described herein these sash rails preferably are formed from lengths of aluminum extrusions. The cross section of each rail is such as to present an inwardly directed glazing bead or pocket which, in the presently described form, is seen to be filled with a rubber-like packing 49 encasing the margins of the glass and effecting a tight and permanent seal between the sash rails and the glass. Packing 49 has sufficient resilience

to insulate and protect the glass against shocks such as may be imposed upon the sash by slamming it against the frame when opening or closing the window.

In the illustrative form frame 20 also is preferably fabricated from extruded sections of aluminum of profiles as shown, for example, in Figures 2 and 5. The frame is provided with an inner channel 50 and an outer channel 52 which extend in side-by-side relationship around the inner perimeter of the frame. In the present embodiment channel 50 is defined (see Figures 2 and 5) by an inner stop bead 54 embodying an outwardly extending flange 56 and a parting bead 58 embodying an inwardly extending flange 60. Channel 52 is defined by stop bead 58 including an outwardly extending flange 62 and an outer stop bead 64 embodying an inwardly extending flange 66.

Sash 30 is shown in Figure 1 to have is rails 34, 36 and 38 seated within channel 50 and sash 32 has its rails 42, 44 and 46 seated within channel 52. From the relationship illustrated in Figure 1 sash 30 may be moved to the right, its rails 34 and 36 sliding within channel 50, to a position directly behind that occupied by sash 32. Similarly, sash 32 may be moved to the left, as viewed at Figure 1, its rails 42 and 44 sliding within the guiding channels 52.

The lower rail 36 of sash 30 (see Figure 5) is provided with an inwardly extending flange 68 and an outwardly extending flange 70. In the normal position of sash 30 the extent to which the lower rail 36 of the sash can be seated in channel 50 of sill 24 is limited by the downwardly facing abutment surfaces presented by flanges 68 and 70. Correspondingly, sash 32 is provided with an inwardly extending flange 72 and an outwardly extending flange 74 which flanges limit the extent to which lower rail 44 can be seated in channel 52 of sill 44.

In order to assure an easy sliding action of the sashes within the frame members and to prevent the passage of moisture and air around the rails of the sashes each of the sashes is provided around its upper, lower and vertical rails with a resilient hardened stainless steel weather strip of channel-like cross section. More particularly, sash 30 has the outer edge of its upper rail 34 encased by a weather strip 76 held in position by machine screws 78 threaded directly into the upper rail. As best shown in Figure 5, weather strip 76 is U-shaped in cross section and each of its legs has an inwardly turned flange 80 which is constrained by the natural resilience of the strip itself in face-to-face relationship with the side walls of rail 34. The intermediate leg portions 82 of the weather strip are bowed outwardly away from the side walls of rail 34 and maintain yielding contact between the opposing surfaces presented by flanges 56 and 60. Thus access of air or moisture from outside to inside around rail 34 is prevented by the sealing contact effected by outer leg 82 and flange 60 and additionally by inner leg 82 and flange 56. The double seal which results not only makes a lasting bar against entrance of adverse weather conditions but also promotes an easy and silent resilient sliding action between the top rail of the sash and the header of the frame when the sash is moved horizontally from one position to another.

As best shown in Figure 2, vertical rail 38 of sash 30 is provided with a weather strip 76 which effects a similar double seal between flanges 56 and 75.

and 60 of jamb 26. In like fashion (see Figures 5 and 2 respectively) the upper rail 42 and the vertical rail 46 of sash 32 are double sealed between the flanges 62 and 66 of channel 52 by like weather strips 76.

In order to prevent unintended entrance of adverse weather conditions between sashes 30 and 32, meeting rail 40 is provided with an outwardly extending flange 84 having a backwardly directed leg 86 presenting an inclined surface 88 facing toward the sash. Meeting rail 40 is similar in cross section to the cross section of meeting rail 48 and both rails can be made from sections extruded by the same die. Meeting rail 40 included an inwardly extending flange 90 provided with a backwardly directed leg 92 presenting an inclined surface 94 facing toward the sash. When the sashes are in close position, as shown in Figure 2, surfaces 88 and 94 engage each other with a slight wedging action which assures a firm and extensive surface to surface contact along the flange portions of the meeting rails so that the weather is effectively barred.

The lower rail 44 of sash 32 (see Figure 5) has its lower portions encased by a weather strip 96 of U-like cross section held in place by machine screws 98. Each of the legs 100 of weather strip 96 is provided with a flange 102. The outer flange 102 is interposed between upper portions of flange 66 and lower portions of flange 74. The inner flange 102 is interposed between upper portions of flange 62 and lower portions of flange 72. The legs 100 also may make resilient lateral contact with the opposing vertical faces of flanges 62 and 66. It will be appreciated that most if not all of the weight of the sash will ordinarily be imposed by flanges 72 and 74 upon flanges 62 and 66 and therefore that weather strip 96 is maintained under some pressure in a position to form a double seal along the inner and outer edges of rail 44 so as to prevent entrance of moisture or cold air. In addition, however, weather strip 96 also functions to promote a smooth and silent sliding action between the sash and the sill member since the coefficient of friction between the hardened steel margins of the weather strip and the underlying aluminum flanges 62 and 66 is relatively small. Thus weather strip 96 not only serves to maintain a complete weather bar but it also eliminates surface to surface contact between the associated aluminum parts and promotes an ease and quietness of operation not commonly obtained in ordinary sliding windows. The lower rail 36 of sash 30 is also fitted with a weather strip 96 which operates along with flanges 56, 60, 68 and 70 in the same manner as that described in connection with the weather strip of rail 44 of sash 32. It will be appreciated that the problems of forming an effective weather bar along the bottom of a horizontally sliding window such as shown herein are more substantial in some respects than those attending the sealing at the sill line of a double hung window, for example, because the seal does not part when the sash is moved, as in a double hung construction, but on the contrary must be such as to permit an easy initial sliding action so that the window may be opened without application of undue force.

In order to lock the windows in the position illustrated in Figure 1, outer sash 32 is provided centrally of its meeting rail with a keeper 104 and inner sash 30 is provided with a latch 106. Keeper 104 is a dihedrally shaped plate having a short leg 108 secured by a machine screw 110

to the face of meeting rail 48 and a long leg 112 passing through a slot through the shank of flange 90 of the meeting rail to present an interiorly accessible detent 114 (see Figure 7). Latch 106 is constrained to vertical sliding movement along meeting rail 40 by means of latch portions 116 and 118 which embrace inner and outer surfaces of meeting rail 40 along with a headed latch screw 120 threaded into the face of the meeting rail and passing through an elongated vertical slot 122 in the latch. The latch includes a dog portion 124 which is normally biased by gravity to the position illustrated in Figure 5 where it enters detent 114 of the keeper to lock the sashes in close position. The sashes may readily be unlocked by lifting latch 106 and sliding sash 30 to an open position.

It is desirable that the window be fashioned so that one of the sashes may be opened slightly and there locked in adjusted position so as to afford a controlled amount of ventilation without rendering the sashes subject to further opening by an intruder. To this end I provide a series of notches 126 (see Figures 2 and 5) in flanges 56 and 60 of inner sill channel 50. The lower end of meeting rail 40 (see Figures 3 and 4) is equipped with a sliding latch 128. This latch is secured to the meeting rail by a headed screw 130 threaded into the meeting rail and the latch is constrained to vertical sliding movement by slot 132 (see Figure 5) through which screw 130 passes and a slot 134 in which an elongated hub 136 formed on meeting rail 40 operates.

Latch 128 includes a finger piece 138 by which the latch may conveniently be raised or lowered. The latch is wider as measured transversely with respect to sill 24 than the opposing faces of flanges 56 and 60 and accordingly the latch may be lowered through a selected pair of opposing notches 126 to lock the sash against sliding movement in either direction. Since the latch is located on the meeting rail of the sash it is sufficiently remote from the window opening as to be substantially inaccessible to an intruder on the outside of the window. Thus the window may be opened a matter of several inches or some adjusted fraction thereof and there secured in place by latch 128 and the sash 30 cannot later be further opened by an unauthorized person outside the window.

In order to prevent unintended opening of outer sash 32 when its keeper 104 is released by latch 106 on the inner sash I provide a pivoted catch 140 (see Figures 2 and 8) secured by a pivot screw 142 set in parting bead 53. Latch 140 includes a detent portion 144 which in the locked position passes through a slot 146 in a handle portion 148 centrally carried by vertical rail 46. When the detent 144 is engaged with handle 146 sash 32 cannot be moved away from the closed position illustrated in Figure 2.

Sash 30 is provided with a handle 150 centrally carried upon vertical rail 38 for use in facilitating opening or closing the sash. A catch corresponding to catch 140 may be employed with handle 150 in addition to, or as a substitute for, the locking mechanism on the meeting rails.

In warm weather it is usually desirable to provide a large window opening and for this reason the larger the opening that can be effected in any given window, the more satisfactory the window is likely to be during warm weather. My invention makes it possible for the ordinary home owner to remove both of the sashes from

the window frame thus creating a window opening of maximum size. It is also to be noted that the sashes may be removed for cleaning purposes; a sash may be removed, carried to a driveway or laundry tub, washed with soap and running water, wiped like a large dish, and returned to place. In Figure 1 a block 150 is shown secured by a screw 152 in the channel 50 of header 54. Block 150 is one of a pair of blocks 150 and 154 the positions of which in channel 50 are indicated in Figure 1. When sash 30 is partially closed it cannot be bodily lifted sufficiently to unseat its bottom rail 36 from channel 50 in sill 24 because blocks 150 and 154 make contact with the upper surfaces of the upper rail. When sash 30 is moved substantially to the right, as viewed in Figure 1, however, upper rail 34 may be relatively deeply recessed in channel 50 of the header so as completely to unseat rail 36 from channel 50 in the sill. In this fashion the sash 30 may readily be removed from the window opening. Similarly, channel 52 of header 22 is provided with blocks 156 and 158 positioned as indicated in Figure 1 so that when sash 32 is in partially closed position its lower rail cannot be unseated from channel 52 in sill 24. However, by moving sash 32 to the left, as viewed in Figure 1, so that its vertical rail 46 has passed to the left of block 156, the upper rail 42 of the sash may be deeply recessed into channel 52 of header 22 so as to unseat lower rail 44 from channel 52 in sill 24. Thus sash 32 also may readily be bodily removed from the window frame 20.

A weather block 160 is shown secured by a screw 162 in the longitudinal center of parting bead 53 of header 22. Block 160 overlies the upper ends of flanges 84 and 90 which form the weather seal between the meeting rails. Thus it becomes feasible to terminate the upper ends of the sealing flanges of the meeting rails at the lowermost level reached by the downwardly extending legs of weather strips 76 along upper rails 34 and 52. The frame is provided with weep holes, one of which is indicated in Figure 2 at 162, as is conventional.

From the foregoing it will be seen that a sliding window construction made in accordance with the present invention is well adapted to attain the ends and objects hereinbefore set forth and to be economically manufactured since both the assembled article and the method of making it are suited to common production methods and are susceptible to a wide latitude of variations as may be desirable in adapting the invention to different applications.

As various embodiments may be made of the above invention and as changes might be made in the embodiments above set forth, it is to be understood that all matter hereinbefore set forth or shown in the accompanying drawings is to be interpreted as illustrative and not in a limiting sense.

I claim:

1. A sash construction including: a sash rail having a cross-sectional portion substantially defining three sides of a rectangular shape having a base and two sides extending therefrom, and a weather stripping element of U-like cross section enveloping at least a part of the rectangular portion of said rail; the inside of the base of the U of the U-like element being secured to the outside of the base of the rail portion, the legs of the U of the U-like element lying along the sides of the rail portion and enveloping said portion therebetween, each side of the rail por-

tion including projecting portions extending outwardly therefrom in a direction substantially perpendicular to the plane of the sash, each leg of the element having its outer end turned outwardly substantially coextensively and in juxtaposition with said projecting portions, and each leg of said element between its outer end and where it joins the base of the U including a portion tending resiliently to move slightly away from the face of the adjacent side of the rail 10 portion.

2. A window construction including: a sill member embodying a parting bead and a stop bead defining a sash guiding channel, a sash rail having a portion received within said channel embodying a base and side portions extending from the base and out of said channel, and a weather-stripping element of U-like cross section enveloping the rail portion received within said channel; the inside of the base of the U of the U-like element being secured to the outside of the base of the rail, the legs of the U of the U-like element lying along the sides of the rail and enveloping said rail portion therebetween, each side of the rail portion including projecting portions extending outwardly therefrom in a direction substantially perpendicular to the plane of the sash, each leg of the element having its outer end turned outwardly substantially coextensively and in juxtaposition with said projecting portions, and such leg outer ends being interposed between said projecting portions and opposing portions of said beads to prevent surface-to-surface contact between said sash projecting portions and said bead portions and to transfer thrusts from said sash rail to said bead portions.

3. A metallic window construction including a frame comprising substantially vertical jambs, a substantially horizontal header and a substantially horizontal sill, each of said header and sill having a sash-receiving channel therein, a sash slidably mounted in both of said channels for horizontal movements, said sash comprising substantially vertical stiles and upper and lower substantially horizontal rails, said sill including vertically extending spaced flanges forming said channel in said sill and having their longitudinal edges spaced from each other for the reception of the lower rail of said sash, a weather strip and friction-reducing member carried by said lower rail of said sash and engaging and slidably on said flanges on said sill with said sash, said weather strip and friction-reducing member being disposed between said lower sash rail and the adjacent edges of said flanges on said sill to isolate said lower rail from said flanges.

4. The combination of elements recited in claim 3 wherein said weather strip and friction-reducing member is provided along its longitudinal edges with outwardly extending flanges which engage, rest upon and are slidable upon adjacent faces of said flanges on said sill.

5. The combination of elements recited in claim 4 wherein said header is provided with flanges forming the sash receiving channel therein in which flanges have spaced longitudinal edges forming an opening for the reception of the upper rail of said sash, said upper rail extending into said opening and a weather strip and friction reducing member mounted on said upper rail and having depending resilient flange portions extending longitudinally between said upper rail and adjacent faces of said flanges of said header

5 to space said upper rail within said channel opening and isolate said rail from said flanges.

6. A window construction including a frame comprising a pair of spaced substantially vertical jamb members and a pair of substantially horizontal oppositely-disposed parallelly-extending sash-guiding members, and a sash slidably mounted between and in said sash-guiding members for horizontal movement in the plane of the sash; said members each having an elongated channel formed therein opening toward the opposite member, the sash having a pair of spaced substantially vertical stiles and a pair of substantially horizontal oppositely-disposed parallelly-extending rails, one rail being received along its length by the channel of one of said horizontal members and the other rail being received along its length by the channel of the other horizontal member, the one rail having flange portions extending therefrom substantially perpendicularly to the plane of the sash, supporting said sash and limiting the extent to which said one rail can enter the channel of the one horizontal member, the other rail having side walls adapted for relatively deep reception by the channel of the other horizontal member, the sash being biased toward the one horizontal member whereby the one rail ordinarily is seated in the channel of the one horizontal rail as deeply as the flange portions will permit and is supported in such position for sliding movements.

7. A window construction including a frame comprising a pair of spaced substantially vertical jamb members and a pair of substantially horizontal oppositely-disposed parallelly-extending sash-guiding members, and a sash slidably mounted between and in said sash-guiding members for horizontal movement in the plane of the sash; said members each having an elongated channel formed therein opening toward the opposite member, the sash having a pair of spaced substantially vertical stiles and a pair of substantially horizontal parallelly-extending oppositely-disposed rails, one rail being received along its length by the channel of one of said horizontal members and the other rail being received along its length by the channel of the other horizontal member, the one rail having flange portions extending therefrom substantially perpendicularly to the plane of the sash, supporting said sash and limiting the extent to which said one rail can enter the channel of the one horizontal member, the other rail having side walls adapted for relatively deep reception by the channel of the other horizontal member, the sash being biased toward the one horizontal member whereby the one rail ordinarily is seated in the channel of the one horizontal rail as deeply as the flange portions will permit and is supported in such position for sliding movements, the other horizontal member including an abutment portion defining a stop surface limiting the extent to which the other rail may be moved into the channel of such member, the abutment portion being located toward one end of the other horizontal member and the other end of such member being free of such abutment portion, whereby when the sash is adjacent the abutment-free end of each member its other rail may be moved into the channel of such member to unseat the one rail from the channel of the one member so that the sash may be removed.

8. A window construction including a frame comprising a pair of spaced substantially vertical jamb members and a pair of substantially

horizontal oppositely-disposed parallelly-extending sash-guiding members, and a sash slidably mounted between and in said sash-guiding members for horizontal movement in the plane of the sash; said members each having an elongated channel formed therein opening toward the opposite member, the sash having a pair of spaced substantially vertical stiles and a pair of substantially horizontal parallelly-extending oppositely-disposed rails, one rail being received along its length by the channel of one of said horizontal members and the other rail being received along its length by the channel of the other horizontal member, the one rail having flange portions extending therefrom substantially perpendicularly to the plane of the sash, supporting said sash and limiting the extent to which said one rail can enter the channel of the one horizontal member, the other rail having side walls adapted for relatively deep reception by the channel of the other horizontal member, the sash being biased toward the one horizontal member whereby the one rail ordinarily is seated in the channel of the one horizontal member as deeply as the flange portions will permit and is supported in such position for sliding movements, and a weather stripping element of channel-like cross-section carried by said one rail between the one rail and its flange portions and the adjacent portions of the one horizontal member whereby surface-to-surface sliding contact between the one rail and the one horizontal member is prevented.

9. A window construction including a frame comprising a pair of spaced substantially vertical jamb members and a pair of substantially horizontal oppositely-disposed parallelly-extending sash-guiding members, and a sash slidably mounted between and in said sash-guiding members for horizontal movement in the plane of the sash; said members each having an elongated channel formed therein opening toward the opposite member, the sash having a pair of spaced substantially vertical stiles and a pair of substantially horizontal parallelly-extending oppositely-disposed rails, one rail being received along its length by the channel of one of said horizontal members and the other rail being received along its length by the channel of the other horizontal member, the one rail having flange portions extending therefrom substantially perpendicularly to the plane of the sash, supporting said sash and limiting the extent to which said one rail can enter the channel of the one horizontal member, the other rail having side walls adapted for relatively deep reception by the channel of the other horizontal member, the sash being biased toward the one horizontal member whereby the one rail ordinarily is seated in the channel of the one horizontal member as deeply as the flange portions will permit and is supported in such position for sliding movements, resilient weather-stripping elements of channel-like cross-section secured to and enveloping the edges of the rails and forming a weather bar between the rails and horizontal members, the weather-stripping element secured to the one rail having outwardly-extending edge portions interposed between the flange portions of the one rail and the adjacent portions of the one horizontal member whereby surface-to-surface sliding contact between the one rail and horizontal member is prevented.

10. A window construction including a frame comprising a pair of spaced substantially verti-

cal jamb members and a pair of substantially horizontal oppositely-disposed parallelly-extending sash-guiding members, and inner and outer sashes slidably mounted in and between said horizontal members for horizontal movements therebetween each in its own plane; the horizontal members each having inner and outer closely spaced elongated channels formed therein and opening toward the opposing horizontal member, each sash having a pair of spaced substantially vertical stiles and a pair of horizontal substantially parallelly-extending oppositely-disposed rails, one rail of the inner sash being received along its length by the inner channel of one horizontal member and the other rail of the inner sash being received along its length by the inner channel of the other horizontal member, one rail of the outer sash being received along its length by the outer channel of the one horizontal member and the other rail of the outer sash being received along its length by the outer channel of the other horizontal member, the one rail of each sash having flange portions extending therefrom substantially perpendicularly to the plane of the sash, supporting said sash and limiting the extent to which said one rail can enter its channel in the one horizontal member, the other rail of each sash having side walls adapted for relatively deep reception by its channel in the other horizontal member and each sash being biased toward the one horizontal member whereby the one rail of each sash ordinarily is seated in its channel as deeply as the flange portions will permit and is supported in such position for sliding movement.

11. A window construction including a frame comprising a pair of spaced substantially vertical jamb members and a pair of substantially horizontal oppositely-disposed parallelly-extending sash-guiding members, and inner and outer sashes slidably mounted in and between said horizontal members for horizontal movements therebetween each in its own plane; the horizontal members each having inner and outer closely spaced elongated channels formed therein and opening toward the opposing horizontal member, each sash having a pair of spaced substantially vertical stiles and a pair of substantially horizontal parallelly-extending oppositely-disposed rails, one rail of the inner sash being received along its length by the inner channel of one horizontal member and the other rail of the inner sash being received along its length by the inner channel of the other horizontal member, one rail of the outer sash being received along its length by the outer channel of the one horizontal member and the other rail of the outer sash being received along its length by the outer channel of the other horizontal member, the one rail of each sash having flange portions extending therefrom substantially perpendicularly to the plane of the sash, supporting said sash and limiting the extent to which said one rail can enter its channel in the one horizontal member, the other rail of each sash having side walls adapted for relatively deep reception by its channel in the other horizontal member and each sash being biased toward the one horizontal member whereby the one rail of each sash ordinarily is seated in its channel as deeply as the flange portions will permit and is supported in such position for sliding movement, the inner channel of the other horizontal member including abutment means toward one end limiting movement of the inner sash into the inner channel at its one end, and

the outer channel of the other horizontal member including abutment means toward its other end limiting movement of the outer sash into the outer channel at its other end.

12. A metallic window construction including: a frame comprising substantially vertical jambs and substantially horizontal header and sill members each having a sash-receiving channel therein, a sash including substantially vertical stiles and upper and lower rails, said rails extending into and slidably mounted in both of said channels of said sill and header for horizontal movements of adjustment, said sash having flange portions on said lower rail of said sash extending inwardly and outwardly therefrom and having downwardly facing surfaces, said sill member including horizontal supporting portions having upwardly facing surfaces spaced from said downwardly facing surfaces on said flange portions, said flange portions and said supporting portions bearing the weight of said sash, a resilient weather strip carried by said downwardly-facing surfaces and interposed between said surfaces of said flange portions and said supporting portions, preventing surface-to-surface contact therebetween and resiliently positioning said lower rail of said sash laterally between said supporting portions.

13. A metallic window construction including: a frame comprising substantially vertical jambs and substantially horizontal header and sill members each having a sash-receiving channel therein, a sash including substantially vertical stiles and upper and lower rails, said rails extending into and slidably mounted in both of said channels of said sill and header for horizontal movements of adjustment, said sash having flange portions on said lower rail of said sash extending inwardly and outwardly therefrom and having downwardly-facing surfaces, said sill member including horizontal supporting portions having upwardly-facing surfaces spaced from said downwardly-facing surfaces on said flange portions, said flange portions and said supporting portions bearing the weight of said sash, a resilient weather strip carried by said surfaces and interposed between said surfaces of said flange portions and said supporting portions, preventing surface-to-surface contact therebetween and resiliently positioning said lower rail of said sash laterally between said supporting portions, and a region of clearance between said sash and said header and sill members to permit the sash when slid to an adjusted horizontal position to be removed bodily from said frame.

14. A metallic window construction including: a frame comprising substantially vertical jambs, a substantially horizontal header having a sash-receiving channel therein and a substantially horizontal sill having a sash-receiving channel therein, a sash including substantially vertical stiles and substantially horizontal upper and lower rails extending into and slidably mounted in both of said channels of said sill and header for horizontal movements of adjustment; said sash having flange portions on said lower rail extending inwardly and outwardly therefrom and having downwardly-facing surfaces, said sill member including substantially horizontal supporting portions having upwardly-facing surfaces spaced from said downwardly-facing surfaces on said flange portions, said flange portions and said supporting portions bearing the weight of said sash, and a resilient metallic weather strip interposed between said surfaces of said flange portions and said supporting portions, preventing surface-to-surface contact therebetween and resiliently positioning said lower rail of said sash laterally between said supporting portions, said weather strip being carried by said lower rail and having yieldable portions disposed between said lower rail of said sash and said supporting portions on said sill.
